EXTRUDED STRUCTURAL ELEMENT FOR BUILDINGS

Lindell N. Edwards, St. Louis, Mo., assignor to
Universal Modular Structures, Inc., St. Louis, Mo.

Filed Feb. 14, 1972, Ser. No. 226,378

Term of patent 14 years

Int. Cl. D25—01

U.S. Cl. D13—1 H

FIG. 1.

FIG. 2.

FIG. 3.

FIG. 1 is a perspective view of the upper end of an extruded structural element for buildings which embodies my new and ornamental design.

FIG. 2 is an elevational view of the upper end of the facing side of the extruded structural element, which faces downwardly and to the right in FIG. 1, and the opposite side has flat surfaces on its projecting parts, the cross section being uniform from top to bottom, and

FIG. 3 is a sectional view, on an enlarged scale, through the extruded structural element for buildings shown in FIG. 1, and it is taken along the plane indicated by the line 3—3 in FIG. 2.

The extruded structural element for buildings is broken away at the lower end thereof in FIGS. 1 and 2 to indicate indeterminate length.

I claim:

The ornamental design for an extruded structural element for buildings, as shown and described.
